UNITED STATES PATENT OFFICE.

GEORGE GARRATT KENT, OF LONDON, ENGLAND.

CROCHET COTTON OR WOOL HOLDING DEVICE.

1,169,967.

Specification of Letters Patent.

Patented Feb. 1, 1916.

Application filed April 19, 1913. Serial No. 762,258.

To all whom it may concern:

Be it known that I, GEORGE GARRATT KENT, a subject of Great Britain and Ireland, residing at No. 5 Kitchiner road, East 5 Michley, London, in the county of Middlesex, England, have invented new and useful Improvements in and Relating to Crochet Cotton or Wool Holding Devices, of which the following is a specification.

10 My invention relates to improvements in revolving holders for balls, or bobbins, of wound cotton, wool, silk, yarn, or other like material, and has particular reference to that class of device in which balls, bobbins, 15 or the like, of crochet cotton, or wool, are suspended to enable the ball or bobbin to be readily unwound during the operation of crocheting and knitting. Heretofore other devices for these purposes have been 20 employed, consisting, in one instance, of a closed wire frame to contain or hold cotton or wool, wound upon it, having a hooked link in which the upper end of the frame rotates, and an open hook for attachment to the garment 25 of the operator, while for suspending the balls a straight wire rod provided at its lower end with a pivoted cross bar at right angles thereto, against which the ball loosely rests, has been used, the upper end 30 of the wire having a hooked link, and open hook. Such open hooks are liable to cause damage to the wearer or anyone coming in contact with same. A safety pin, having a 35 twisted loop on one of its bars, and adapted to receive a rotatable link attached to a spring hook for suspending the holder from a garment or table-cloth has also been proposed, but the constant insertion of the safety pin, tends to damage the garment or material to which it is affixed when 40 brought into use.

The object of my invention is not only to avoid these defects but to provide an improved device by the use of novel and 45 simpler means. I attain these objects by the mechanism illustrated in the accompanying drawing, in which:—

Figure 1. is a front elevation of my improved device. Fig. 2. is a side elevation 50 of same. Fig. 3. is a front elevation of the device with the bolt ring removed, when it is not desired to use same, and Fig. 4. is a side elevation of Fig. 3.

Similar letters refer to like parts in the 55 several views.

My invention comprises an improved

holder and base piece for the ball, or bobbin, and the combination therewith of a revolving spring swivel which may be suspended by a bolt or spring ring, or may be capable 60 of attachment to an ordinary bracelet, or bangle worn by the operator, or the swivel holder and base piece may be attached direct to a bracelet, or bangle, forming part of the device.

Referring to the drawing, Fig. 1, A is the holder, B the base piece for supporting the ball, or bobbin, C, which is indicated in dotted lines, such holder consisting of a wire or any other material, and provided at its 65 upper end with a narrow half round bend D, and bowed outward from the center, the legs as they descend to their ends E being brought closer together again and placed in the base, which may be formed of a disk of 70 metal or any other nonflexible material, of any diameter or thickness, to allow the legs to be held secure to the base B. At the upper end of the improved holder a revolving 75 spring swivel F, or the like, is attached, and in the rotating ring G of the swivel a bolt 80 ring, or spring ring H, may be inserted, to allow of the swivel, holder and base, being suspended from the bracelet, or bangle I, when such bracelet or bangle does not form 85 part of the device. The holder is adapted to fit more or less tightly in the hole or center of a crochet ball, bobbin, or the like, and the base prevents any possibility of the ball, or bobbin, falling from the holder. The 90 holder is disconnected from the swivel F, to enable the ball, or bobbin, to be placed in position for use.

As illustrated in Figs. 3 and 4, I may dispense with the bolt ring, H, shown in 95 Figs. 1 and 2, and connect the revolving spring swivel F, or the like, directly to the bracelet or bangle I.

Apparatus of the character described is exceedingly serviceable, and of general 100 utility for the purpose intended. It is readily brought into use, and easily attached, or detached, to allow the crochet ball, or bobbin being placed in position, while it insures the free unwinding of the ball, or 105 bobbin, during the operation of crocheting, or knitting.

What I claim is:

1. In a device for holding crochet cotton, wool or the like in ball form, a flat base 110 member, a spindle secured centrally thereto and projecting upwardly at right angles to

the plane of said base, said spindle having a loop at its upper end and being designed to frictionally receive and hold the material thereon against rotation with respect to the 5 spindle, an open bracelet to be fitted to the user and a hook swivel detachably connected to the loop portion of the spindle and engaged with the bracelet to permit the spindle, base and ball of material to rotate with 10 respect to the bracelet, as one.

2. A portable and revolving holder for balls of crochet cotton and the like in wound form, comprising a solid base in the form of a plate, a spindle secured thereto centrally 15 and extending at right angles therefrom, said spindle comprising a wire member rebent intermediate its ends and with its free ends brought together and anchored in the base, the leg portions between the rebent 20 part and said ends being bowed outwardly to frictionally engage and hold the ball of material thereon, said base preventing displacement of said material from said spindle, and a swivel secured to the bight portion 25 of the spindle and adapted for attachment to the bracelet of an operator.

3. A portable and revolving holder for balls of crochet cotton and the like in wound form, comprising a solid base in the form of 30 a plate, a spindle secured thereto centrally and extending at right angles therefrom, said spindle comprising a wire member rebent intermediate its ends and with its free ends brought together and anchored in the 35 base, the leg portions between the rebent part and said ends being bowed outwardly

to frictionally engage and hold the ball of material thereon, said base preventing displacement of said material from said spindle, and a swivel secured to the bight portion 40 of the spindle, a swivel secured to the rebent upper end of the spindle to permit said spindle, base and material to revolve with respect thereto and an expansible bracelet for connection with said swivel to suspend said part.

4. A portable and revolving holder for balls of crochet cotton and the like in wound form, comprising a solid base in the form of a plate, a spindle secured thereto centrally and extending at right angles therefrom, said spindle comprising a wire member rebent intermediate its ends and with its free ends brought together and anchored in the base, the leg portions between the rebent part and said ends being bowed outwardly to frictionally engage and hold the ball of material thereon, said base preventing displacement of said material from said spindle, a swivel secured to the rebent upper end of the spindle to permit said spindle, base and material to revolve with respect thereto, an expansible bracelet and means for detachably connecting the swivel 55 to the bracelet.

In testimony whereof I have signed my name to this specification in the presence of two subscribing witnesses.

GEORGE GARRATT KENT.
